PROCESS FOR PREPARING PENTAMETHYL-CYCLOPENTAPHOSPHINE

William A. Henderson, Jr., Stamford, Conn., assignor to American Cyanamid Company, New York, N.Y., a corporation of Maine
No Drawing. Filed June 5, 1961, Ser. No. 114,655
7 Claims. (Cl. 260—606.5)

The present invention relates to a novel process for the preparation of cyclopentaphosphine. More particularly, it relates to the preparation of pentamethylcyclopentaphosphine.

It is known that methylidifluorophosphine can be converted to a 5-membered heterocyclic phosphorous compound. The conversion takes place either upon heating or storing such methylidifluorophosphine. Unfortunately, however, the method for conversion of the particular alkylidifluorophosphine is not wholly satisfactory. In order to obtain the desired conversion, only certain alkylidihalophosphines can be so-employed. It has been found that methylidifluorophosphine is the sole reactant capable of such conversion. Hence, the aforementioned process is a rather limited one. Heating the particular dihalophosphine derivative or storing the same for prolonged periods of time, moreover, will induce cyclization to form pentamethylcyclopentaphosphine but only in poor yields. This is attributed to the fact that there is concomitantly obtained a substantial amount of methyltetrafluorophosphine as an undesired side product. Due to the limitation of initial reactant selection and the attendant low yields of pentamer, the over-all process has not been commercially attractive. The present invention has for its object the provision which obviates the hereinabove mentioned difficulties.

To this end, it has been found that any methylidihalophosphine can unexpectedly be converted to the corresponding cyclopentamer. The reactant, methylidihalophosphine, can include the fluoro, chloro, bromo or iodo radicals. Surprisingly, the reaction can be carried out in a convenient manner by causing the particular methylidihalophosphine to react with a reducing metal, whereby the corresponding cyclopentamer is obtained in good yield and purity, and usually in excess of at least fifty percent (50%) based on the weight of that reactant. In the process of the instant invention, no alkylphosphinetetrahalide as an impurity is obtained.

According to the process of the instant invention, a methylidihalophosphine is subjected to the action of a reducing metal, such as magnesium, sodium, potassium or lithium. Conversion or reduction of a dihalophosphine is slowly carried out at a temperature ranging from about -80° C. to about $+100^{\circ}$ C., and preferably from -40° C. to about 25° C. Reaction is terminated when the reducing metal has been completely reacted and recovered in the form of the halide salt. Usually this occurs within about twenty to about thirty hours at atmospheric pressure.

Advantageously, a number of dihalophosphines may be employed for purposes of ready conversion. These are:

Methyl difluorophosphine,
Methyl dichlorophosphine,
Methyl dibromophosphine, and
Methyl diiodophosphine.

Methyl dichlorophosphine is preferred as the reactant, for the reason that it is more readily available and is storage-stable for prolonged periods.

In general, the reduction reaction is preferably conducted in an inert ethereal solvent. Illustrative of such solvents are: ether, dioxane, tetrahydrofuran, dimethyl ether of diethylene glycol and equivalents thereof.

2

Equivalent amounts of reducing metal and a methylidihalophosphine are brought into reactive combination. Where lesser amounts of the methylidihalophosphine are used, a maximum yield of resultant cyclopentamer is not obtained. Thus, in order to insure completeness of reaction so as to obtain maximum yields, at least an equivalent amount of the reactant will be required.

The following illustrative examples will serve to more fully describe the instant invention. These, however, are not to be taken as limitative thereof. Unless otherwise noted, the parts given are by weight.

EXAMPLE 1

Preparation of Pentamethylcyclopentaphosphine

In a flat-bottom vessel equipped with an efficient stirrer are placed 2.04 parts of lithium ribbon in 30 parts of dry tetrahydrofuran under a nitrogen atmosphere. To the flask are slowly added with stirring at -40° C. 17 parts of methylidichlorophosphine. The mixture is brought up to room temperature and stirred until all the metal has reacted. Solvent is then removed and the liquid material boiling up to 200° C. at 1 mm. Hg pressure collected. The liquid so-collected is redistilled to yield 5.0 parts or 74% of pentamethylcyclopentaphosphine, having a boiling point of from 110° C. to 112° C. at about 1 mm. Hg pressure.

Analysis in percent: Calculated—C, 26.10; H, 6.59; P, 67.33. Found—C, 26.37; H, 6.80; P, 67.30.

EXAMPLE 2

The procedure of Example 1 is repeated in every detail except that the reducing agent, lithium, is omitted whereby conversion to the cyclopentaphosphine is attempted. None of the cyclopentaphosphine derivative is detected.

EXAMPLE 3

Example 1 above is repeated, except that the reducing agent is omitted and the phosphine reactant is heated to about 100° C. Conversion to the cyclopentamer is not observed.

EXAMPLE 4

The procedure of Example 1 above is followed except that 30.3 parts of methylidibromophosphine are substituted for the methylidichlorophosphine reactant. Pentamethylcyclopentaphosphine yield of 5.4 parts corresponding to 79 percent is obtained.

Similar high yields of pentamethylcyclopentaphosphine are obtained when either methylidifluorophosphine or methylidiodophosphine is substituted for the methylidibromo reactant above.

Advantageously, the product obtained from the process of the present invention finds utility as a polymerization accelerator for epoxy-type monomers. Thus, the polymerization of diglycidyl ether of isopropylidene diphenol can be easily accomplished.

I claim:

1. A process for preparing pentamethylcyclopentaphosphine which comprises: bringing into reactive combination at a temperature between about -80° C. and $+100^{\circ}$ C. in the presence of an inert solvent for each of the reactants substantially equivalent quantities of a methylidihalophosphine and a reducing metal selected from the group consisting of sodium, potassium, lithium and magnesium, causing the reaction to continue for at least about twenty hours, and recovering so-formed pentamethylcyclopentaphosphine in good yield and purity.
2. A process according to claim 1, in which the methylidihalophosphine is methylidifluorophosphine.
3. A process according to claim 1, in which the methylidihalophosphine is methylidibromophosphine.

4. A process according to claim 1, in which the methyl-dihalophosphine is methylidiiodophosphine.

5. A process according to claim 1, in which the temperature for carrying out the reaction is maintained at between about -40° C. and $+25^{\circ}$ C.

6. A process according to claim 1, in which the inert solvent is tetrahydrofuran.

7. A process according to claim 1, in which the methyl-dihalophosphine is methyl dichlorophosphine.
